(57) **CLAIM**

The ornamental design for a hand stamp holder, as shown and described.

DESCRIPTION

FIG. 1 is a perspective view of the hand stamp holder according to the present invention;

FIG. 2 is a top plan view, the bottom plan view being substantially identical;

FIG. 3 is an elevation view of one side of the hand stamp holder, the other side being substantially identical thereto;

FIG. 4 is an elevational view of one end; and,

FIG. 5 is an elevational view of the opposite end.
